PRESS FOR DRAWING BLANKS

Frank H. Maloney, Elmhurst, Long Island, N. Y.,
assignor to Brass Goods Manufacturing Co.,
Brooklyn, N. Y., a corporation of New York

Application March 10, 1942, Serial No. 434,040

15 Claims. (Cl. 113—113)

This invention relates to a drawing press for drawing thin metal blanks, which have been previously blanked out from thin sheet metal, into cups which are intended later to be further drawn into the shape of bullet packets. In the past there has been difficulty in feeding such thin metal blanks from a magazine in which the blanks are stored in stack form to a drawing die.

The blanks usually do not come from the blanking press perfectly flat, but the major portion of them are somewhat curved so that they are presented to the feeding mechanism at the mouth of the stack in different planes, the peripheral edge of a blank which is presented with its convex surface downwardly being somewhat higher than the peripheral edge of a perfectly flat blank. This presentation of the blanks at the mouth of the stack in different planes due to their curvature causes an irregular feeding of the blanks, and often causes the feeding mechanism at the mouth of the stack to become jammed so that feeding of the blanks is interrupted.

It is a principal object of the present invention to overcome this difficulty by removing the lowermost blank from the stack and separating it from the remaining blanks therein by transporting it individually sidewise into a guide member which is in alignment with the drawing die, and then transporting the blank individually along such guide member to the die, the guide member being designed to constrain the blank during its motion and deliver it in proper position to the die.

It is an important feature of the invention that all the blanks, irrespective of whether they are flat or slightly curved, are presented at such guide member with their peripheral edges at the same level or in the same plane, so that they may be pushed along a hollow guideway provided in such guide member by means of a thin push finger which is reciprocated therein and serves to deliver them individually to the drawing die. This object is secured by removing the blanks individually from the bottom of the stack by means of a reciprocable slide member which is provided with a recess into which the bottom portions of such blanks may extend which happen to be non-planar, and are presented at the bottom of the stack with their convex surfaces down. This recess is so designed that blanks presented at the bottom of the stack, which are flat or are disposed with their convex surfaces disposed upwardly, do not extend into it with the result that the peripheral edges of all the blanks are at the same level or in the same plane as they leave the stack irrespective of whether the blanks are perfectly flat or happen to be curved upwardly or downwardly.

Where a multiple unit press is utilized having, for example, three forming dies provided with

three guide members for guiding the blanks to the several dies, it is a further feature of the invention that a single reciprocable slide member is arranged to remove the blanks from three magazines in which they are disposed in stack form, and deliver them to the three guide members. This single slide member is provided with three different recesses of the type heretofore described for receiving the blanks and advancing them into the aforementioned guide members. Other objects of the invention will become apparent as the description thereof proceeds.

For a better understanding of the invention reference is made to the following description taken in connection with the accompanying drawings, in which:

Fig. 1 is a fragmentary side view of a multiple unit drawing press embodying the invention;

Fig. 2 is a fragmentary front view of the drawing press shown in Fig. 1;

Fig. 3 is a sectional view of the press of Fig. 1 taken on the section line 3—3 thereof in the direction of the arrows;

Figs. 4 and 5 are fragmentary sectional front views on an enlarged scale showing a portion of the feed means for withdrawing the blanks from a magazine and advancing them toward the drawing die;

Fig. 6 is a fragmentary top plan view showing a reciprocable slide member of Fig. 4;

Fig. 7 is a vertical sectional view showing on an enlarged scale a portion of the slide of Fig. 6;

Figs. 8, 9 and 10 are fragmentary sectional views showing on an enlarged scale different arrangements the blanks may assume at the mouth of a magazine as they are presented to the feed slide for removal from the magazine;

Fig. 11 is a fragmentary vertical sectional view showing one of the punches and drawing dies of the press of Fig. 1 and a portion of the means for feeding the blanks;

Fig. 12 is a top plan view of one of the drawing die units partially separated from its cooperating structure;

Fig. 13 is a fragmentary vertical sectional view taken on the line 13—13 of Fig. 1 showing the construction of the guideway for guiding the blanks as they are advanced rearwardly toward the drawing die;

Fig. 14 is a top plan view showing one of the drawing dies and its supporting ring; and

Fig. 15 is a vertical sectional view showing the construction of the mouth of a magazine and a portion of the means for removing the blanks individually therefrom.

Referring first to Figs. 1, 2 and 3, the drawing press shown comprises three drawing press units 10, 11 and 12 which are similar and are mounted on a common horizontal supporting plate 13 which is in turn supported on the main

frame F of the press. This frame is carried by the usual supporting base B. Supported on the plate 13 by means of spaced apart blocks 14 is an elongated horizontal plate 15 provided with a groove 16 in which is reciprocable a slide member 17 common to the three press units. A description of the press unit 10 will now be given, it being understood that the construction of the units 11 and 12 is exactly similar and corresponding parts of the different units are accordingly designated by the same reference numerals on the drawings.

The slide 17 receives the blanks 18, which are to be formed into bullet cups, from the mouth of a vertical magazine 19 and advances them individually to the right in Fig. 3 and deposits them in front of a thin push rod 20. This rod transports them rearwardly and delivers them one by one under a vertically reciprocable punch 21 which presses them through a drawing die 22, Fig. 11, to be later described and which draws or forms them into cups of the desired shape. The slide 17 is reciprocated by means of a link 23 whose other end is connected to an arm 24 which is secured to a shaft 25. This shaft is supported in two bearings 26 formed in a pair of brackets 27 which have portions extending along the top of plate 13 and are secured thereto by the screws 28. The shaft 25 is in turn oscillated by means of a second arm 29 secured thereto and a drive link 30, the upper end of the link 30 being driven by means of a power driven cam or equivalent (not shown).

The means for reciprocating each push rod 20 comprises an arm 31 secured to a shaft 32, the arm 31 at its upper end being provided with an elongated slot 33 (Fig. 1) adapted to receive a pin 33 projecting from a depending lug 34 secured to the front end of push rod 20. As shown in Fig. 2, the several arms 31 are spaced apart on the shaft 32, which is supported for free oscillation in a pair of bearing brackets 35 which are secured to the front face of the plate 13 by the screws 36. The shaft 32 is oscillated in timed relation with the shaft 25 by means of an arm 37 secured to the end thereof and a drive link 38 whose lower end is pivotally connected with arm 37 and whose upper end is reciprocated by means of a power driven cam or equivalent (not shown).

For a more detailed disclosure of the means whereby the metal blanks 18 which have previously been blanked out in a blanking press, are removed individually from the mouth of the magazine 19 reference is made to Figs. 4 to 7 and 15. The magazine 19 is shown as comprising a thin walled tube 39 whose lower end extends into a recess 40 provided in a generally rectangular shaped plate 41 which is secured to the supporting plate 15 by one or more screws 42 (Fig. 15). The front of plate 41 is cut away sloping first rearwardly and downwardly to provide the inclined face 43 and then downwardly to provide the vertical face 44, as shown in Fig. 15. A companion plate 45 has its rear surface shaped to fit against the faces 43 and 44 and the plates are held together to encompass the lower end of the stack of blanks by a pair of screws 46. This construction permits ready access to the blanks at the lower end of the stack by loosening the screws 46 and removing the plate 45 should, for any reason, one or more of the blanks become caught in the lower end of the magazine and interrupt the feed of the blanks.

The slide 17, see Figs. 4 and 6, has secured thereto adjacent each of the magazines 19 by screws 47 a pusher plate 48 which extends above the level of the top of slide 17 and abutting against the right hand end of the plate 48 is a blank supporting plate 49 which is secured to the slide 17 by a screw 50. The plate 49 is recessed, as shown at 51 in Figs. 4, 6 and 7, the wall of the recess being cylindrical near the bottom as indicated at 52 and inclined outwardly and upwardly near the top, as indicated at 53. As the slide 17 reaches its extreme position to the left, the bottom blank of the stack is deposited on the blank supporting plate 49 and on the rightward stroke of the slide the blank is advanced into a rearwardly extending housing 54 which is provided with a shallow groove or channel 55 in which the push rod 20 operates. The right hand wall of the plates 47 and 45 is cut away as is also the left hand wall of the housing 54, as indicated at 56 and 57 in Fig. 4, to clear and pass the bottom blank as it is advanced into the groove 55, the lower end of the wall 56 extending down for some distance along the peripheral edge of the second blank and thereby preventing this blank from being advanced to the right along with the bottom blank of the stack.

It is found that the major portion of the blanks coming from certain blanking presses are not perfectly flat but are somewhat curved. When such blanks are put into a hopper and feed promiscuously to the several magazines 19 by any suitable means (not shown), the blanks arrive at the bottom of a magazine disposed in different relative orders as shown in Figs. 4, 8, 9 and 10. In Fig. 4 the two bottom blanks and the 5th and 6th are shown disposed with their convex faces disposed downwardly while the 3rd and 4th blanks have their convex surfaces disposed upwardly. In Fig. 8 the bottom blanks are both curved and have their convex surfaces disposed upwardly while in Fig. 9 both the blanks are curved and the convex surface of the bottom one is disposed upwardly and that of the other blank downwardly. In Fig. 10 the bottom blank is curved with its convex surface disposed downwardly, and the other blank is curved with its convex surface disposed upwardly. The curvature of the blanks in these figures is somewhat exaggerated for clearness. The diameter of the blanks is slightly greater than the diameter across the top portion of the inclined wall 53 so that the peripheral lower edge of a blank which is flat or is curved and has its convex surface disposed upwardly, does not enter the recess 51 but rests on the flat upper surface of the plate 49. The result is that the peripheral edge 58 of each blank is disposed at the same level as it is deposited on the plate 49 in position to be removed from the stack irrespective of whether the blank is perfectly flat or has its center portion curved upwardly or downwardly. It will also be observed from these figures that the upper wall of the slot 56 is high enough to clear the bottom blank as it leaves the stack and yet is low enough to engage the peripheral edge of the next higher blank in the stack and thus act as a stop to retain this and the higher blanks in the stack while the bottom blank is removed therefrom by the pusher plate 48 and slide 17.

Fig. 5 shows the position of the slide 17 when it is at the extreme right hand end of its stroke and a blank has been advanced fully into the groove 55. The vertical side wall 59 of the groove

prevents the blank 18 from being carried too far to the right due to its inertia as the slide 17 is stopped and starts to move in the opposite direction. The plates 41 and 45 are cut away on their under sides as shown in Figs. 3, 4 and 13 and the housing 54 is shaped to extend into such cut-out as indicated at 60, thereby bringing the groove 55 into which the blank is advanced closer to the mouth of the magazine 19 and making the structure more compact. Referring to Figs. 1 and 2, the front portion of the push rod 20 is supported on two elongated guide plates 61 along which it is slideable, these plates being secured to the bottom face of housing 54.

When the blank is in position in groove 55 it is engaged by the front end of push rod 20, see Fig. 11, which immediately advances it rearwardly and pushes it into a positioning ring 62 which causes the blank to be located and retained in proper position above the die 22. Die 22 in the illustrated embodiment of the invention has the shape shown in Fig. 11 and is adapted to draw the blank into the shape of the bullet cup 63 shown in dotted lines. It will be understood, however, that the invention is not limited to a press for drawing blanks into this particular shape as it is equally well adapted for a press for drawing blanks into many other shapes, according to the shape of the drawing die and blanks used.

The die 22 is seated in a recess formed in a die block 64, the upper surface of which is recessed to receive the blank positioning ring 62, this ring being secured to the die block by two pins 65. The generally cylindrical shaped die block 64 is seated in a counterbored recess 66 (Fig. 12) provided in the upper face of a supporting plate 67 which is secured in position on the main supporting plate 13 by a pair of screws 68-69. The screw 69 passes into a threaded opening 70 provided in a forwardly extending portion 71 of plate 67, the extension 71 being of generally rectangular shape as shown in Fig. 12 and extending forwardly under the plate 15, as shown in Fig. 11. The plate 15 is also arcuately shaped at 72 to abut against the front portion of die block 64. Plate 67 is also provided with a pair of aligned slots 73 adapted to slidably receive a pair of stripper slides 74 whose inner ends are shaped as shown in Fig. 11 and serve as stripper fingers 75 to strip the cup 63 from the punch 21 after the latter has reached its lowest position and commences moving upwardly on its return stroke. The slides 74 are biased inwardly by means of the springs 76, each spring at its inner end bearing against a depending projection 77 formed on the slide. At its outer end each spring is seated in a notch 78 formed in a block 79, each such block being secured in position on the plate 67 by a pin 80 which enters a bore 81 provided in this plate. The motion of each slide 74 inwardly is limited by a downwardly depending lug 82 formed on the end of the slide and which strikes against the outer face of block 79. The die block 64 is clamped in position by means of a generally rectangular shaped clamping block 83 which is counterbored, as indicated at 84, to receive the major of the peripheral wall of the die block. The clamping block 83 is secured to the plate 67 by means of a pair of bolts 85 whose lower ends engage threaded holes 86 provided in plate 67 (only one being shown in Fig. 11). These bolts also pass through a pair of semi-cylindrical notches 87 provided in the edge of the die block 64, see Figs. 12 and 14. Clamping block

83 is also bored to receive a punch guide bushing 88 through which the punch 21 passes. As shown in Figs. 3 and 11, the rear end of housing 54 engages the front face of clamping block 83 and a slot 89 is formed in the latter, which slot is in alignment with the slot 55 in housing 54, the two slots 55-89 forming a straight guideway which guides the blank all the time it is being pushed rearwardly by the push rod 20 until shortly after it reaches the dotted position indicated at 90, Fig. 11, and drops into the positioning ring 62.

After a cup 63 is formed, it passes down through a short tube 91 set in an opening 92 formed in plate 67, through a second and larger opening 93 formed in plate 13 and out through a large opening 94 of the shape shown in dotted lines in Fig. 3, in the main frame F.

From an inspection of the structure described it will be clear that a worn die may be readily removed for repair or replacement by a new one by loosening the bolts 85 and removing the clamping block 83 whereupon the die block 64 may be readily lifted out and taken to a bench where the die 22 may be removed therefrom in an obvious manner. After repair or replacement of the die it is only necessary to place the die block and clamping block 83 in position on the press and again lock the parts in operating position by tightening the bolts 85.

Referring to Figs. 1 and 2, the three punches 21 are all secured to a single operating head or ram 95 which operates in vertical guideways 96 provided in the main frame F. The operating head is driven in the usual manner by any suitable power driven operating means (not shown).

In the operation of the press the bottom blank is removed from each of the magazines 19 as the slide 17 is advanced toward the right by the driving connections heretofore described. The motion of the blanks toward the right continues until the slide reaches its extreme end position when the three blanks are disposed in the guideways 55, one blank in each. At this time the push rods 20 are moved rearwardly by the arms 31 and operating connections previously described, these rods pushing the three blanks off the slide 17 and advancing them along the guideways 55 and through the slots 89 in the clamping blocks 83 (Fig. 11) until each blank falls into its positioning ring 62 and is disposed in proper position above its drawing die 22. The operating head 95 then descends causing the punches 21 to engage the blanks and force them simultaneously through the drawing dies 22 which form the blanks into the shape of the desired cups. The stripping fingers 75 grip the upper edges of the cups as the punches commence to rise and strip the cups from the plungers which are returned to their upper positions. The formed cups pass down through the openings 92, 93 and 94 into a suitable receptacle or are conveyed away to another drawing press by any suitable automatic conveying means (not shown).

I have described what I believe to be the best embodiments of my invention. I do not wish, however, to be confined to the embodiments shown, but what I desire to secure by Letters Patent is set forth in the appended claims.

I claim:

1. In a drawing press, means for automatically feeding thin substantially flat metal blanks individually to the field of operation of a drawing die from a stack of the blanks, comprising a feed member reciprocable in a substantially straight

path and arranged to engage the bottom blank of the stack and move it edgewise along said path to an advanced position in alignment with the die and a second feed member reciprocable in a substantially straight path at an angle to said first mentioned path and arranged to engage an edge of the blank while in said advanced position and advance it to the die.

2. In a drawing press as claimed in claim 1 in which the paths in which the said feed members are reciprocable are disposed at substantially right angles to each other.

3. In a drawing press, means for automatically feeding thin substantially flat metal blanks individually to the field of operation of a drawing die from a stack of the blanks, comprising a feed member reciprocable in a substantially straight path and arranged to remove the bottom blank from the stack and support it while the blank is advanced edgewise along said path to a predetermined position in alignment with the die and a second feed member reciprocable in a substantially straight path and arranged to engage the blank edgewise while the blank is still supported on said first feed member, remove the blank from said first feed member and advance the blank edgewise to the die.

4. In a drawing press as claimed in claim 3 in which a housing is provided, said housing having a slot in which the second feed member is reciprocable and which also serves as a guideway for guiding the blank as it is advanced to the die.

5. In a drawing press, means for automatically feeding thin metal blanks individually to the field of operation of a drawing die from a stack of the blanks, at least some of the blanks in the stack being curved and disposed with their convex surfaces downward; said feeding means comprising a feed member, means for reciprocating said feed member in a substantially straight path towards and away from the stack, the upper surface of said feed member being provided with a recess for receiving and advancing a blank edgewise away from the stack transversely thereof as said feed member is reciprocated, the convex surface of the bottom blank being adapted to extend into said recess, and means on said feed member for engaging at least a portion of the peripheral edge of the bottom blank.

6. In a drawing press as claimed in claim 5, a combination in which the marginal wall of said recess near its upper portion is inclined and is adapted to engage the surface of the bottom blank near its periphery.

7. In a drawing press as claimed in claim 5, a combination in which the area of said recess in the plane of the upper surface of the slide is slightly less than the area of an individual blank whereby a blank which is flat and comes to be disposed at the bottom of the stack does not extend into the said recess.

8. A multiple unit drawing press comprising a plurality of spaced apart drawing dies, a plurality of punches adapted to press thin substantially flat metal blanks through the dies and means for automatically feeding the blanks individually to the dies from a plurality of stacks of the blanks, said feeding means comprising a single feed member reciprocable in a substantially straight path and arranged to engage the bottom blanks of the stacks and move them edgewise to predetermined advanced positions which are in alignment with the respective dies, a plurality of push rods adapted to engage the

blanks while in said advanced positions and advance the blanks to the dies and means for reciprocating said push rods simultaneously.

9. A drawing press as claimed in claim 8 in which said single feed member is provided with a plurality of plates and each plate is provided with a recess adapted to receive the downwardly bent portion of a blank, the recesses in said plates being disposed simultaneously under the bottom blanks of the stacks.

10. In a drawing press, means for automatically feeding thin substantially flat metal blanks individually and successively from a stack of blanks to the field of operation of a drawing die comprising a guide member for said blanks defining a guide channel leading to the field of operation of the die, a feed member reciprocable in a substantially straight path and arranged to receive the bottom blank of the stack and move it edgewise along said path to said guide channel, and a second feed member reciprocable in said guide channel at an angle to said first mentioned path and adapted to engage an edge of the blank in said channel and push said latter blank along the floor of said channel to the field of operation of the die.

11. In a drawing press, means for automatically feeding thin substantially flat metal blanks individually and successively from a stack of blanks to the field of operation of a drawing die comprising a feed member reciprocable in a substantially straight path, and presenting a shoulder adapted to engage the rear edge of the bottom blank of the stack and carry it edgewise forwardly to an advanced position, while the side edges of said latter blank remain free from shoulder restrictions preventing sideways movement of said latter blank; and a second feed member reciprocable towards and away from the field of operation of the die transversely of said path, and adapted to engage a side edge of the blank resting on said first feed member in said advanced position, push said latter blank sideways off said first member and advance it to said field of operation.

12. In a drawing press, means for automatically feeding in recurrent cycles a plurality of substantially flat thin metal blanks simultaneously to the fields of operation of a corresponding number of drawing dies from the bottom of a corresponding number of stacks, comprising a single reciprocable feed member having a plurality of blank receiving means spaced therealong for stripping the bottom blanks of the stacks simultaneously, and moving them edgewise in unison to advanced positions with said feed member, and a plurality of reciprocable secondary feeding members operable in unison to engage said blanks while in said advanced positions and move them simultaneously towards said fields of operations.

13. In a drawing press, the combination comprising means for supporting substantially flat thin metal blanks in a plurality of substantially parallel spaced stacks aligned in a vertical plane, a plurality of drawing dies, a single feed member reciprocable across the bottoms of all of said stack supporting means and having means for stripping the bottom blanks of said stacks simultaneously and advancing them with said feed member to advanced positions, and a plurality of secondary feed members reciprocable in directions transverse to the reciprocable movement of said single feed member, and having means for engaging said blanks in said advanced

positions and advancing them simultaneously to the fields of operation of said dies.

14. In a drawing press, means for automatically feeding thin metal slightly curved blanks individually and successively from a stack containing said blanks to a drawing die, comprising a feed member movable across the bottom of the stack and having means for stripping the bottom blank from said stack and advancing it edgewise away from said stack transversely thereof as said feed member is moved, said feed member having a recess on its upper side adapted to seat the stripped blank, the marginal wall of said recess near its upper portion being inclined to receive the downwardly facing convex sur-

face of a stripped blank, said recess being of such size with respect to the blanks, whereby the upper portion of the edge of the stripped blank will project upwardly above said recess, even if the stripped blank has its convex surface facing downwardly.

15. In a drawing press as set forth in claim 14, in which said feed member moves the stripped blank in an advanced position, and a second feed member is provided movable to engage the upper projecting edge of the blank in said advanced position and move the blank to the field of operation of the die.

FRANK H. MALONEY.
